BOTTLE WRAPPING MACHINE

Michael J. Milmoe, Chicago, Ill., assignor to F. B.
Redington Co., Chicago, Ill., a corporation of
Illinois

Application September 12, 1929, Serial No. 392,025

46 Claims.

(Cl. 93—2)

The present invention relates to a machine for wrapping articles such as bottles and has for one of its objects the moistening of the wrapping paper before the same is used for wrapping the bottle. The wrapping paper while still moist is used to wrap the bottle and thereafter when the wrapping paper dries, the same is pulled tightly about the bottle in view of the fact that when the paper is moistened it has a tendency to stretch and when it again dries out, it contracts and is pulled tightly over the surface of the bottle.

Another object of this invention is the provision of means for cutting a continuous roll of wrapping material into suitable sizes for wrapping purposes, as the wrapping material is being fed through the machine. More specifically, this cutting means comprises knives, on opposite sides of the wrapping material, which move toward each other and sever the wrapping material by a shearing action which begins at one edge of the material and continues across the material to the other edge thereof. The particular means used for moving the knives to cause the shearing action, are a pair of rotatable cylinders which carry the knife plates and, as these knife plates rotate into a position adjacent each other, they cause the aforesaid shearing action.

Another object of this invention is to glue at least one edge of the wrapping paper so that when the article is wrapped, the paper will stay in position on said article and will not permit the wrapping to come loose when the paper begins to dry.

Another object of this invention is the provision of feeding means for feeding the bottles through the machine which comprises a suitable support upon which the bottles are placed on end and fed to a predetermined position where they are automatically grasped and laid on their sides. The bottles are then wrapped while in this position, with the exception of the last fold over the bottom of the bottle and the folds necessary to close the top thereof. The bottles are then raised into an upright position again and the last fold on the bottom of the bottle is made simultaneously with the movement of the bottle to said upright position.

A further object of this invention is the provision of means for wrapping the bottles while the bottles are in motion through the machine, it being unnecessary to stop the movement of the bottles for the purpose of wrapping the material thereabout.

55 A still further object of this invention is the

provision of new and novel mechanisms for accomplishing the purposes set forth above.

In the drawings:—

Fig. 1 represents an elevational view of the left-hand end of the machine as viewed from the front thereof with the preliminary feeding means removed;

Fig. 2 is a view similar to Fig. 1 showing the right-hand end of the machine;

Fig. 3 is a plan view of that end of the machine shown in Fig. 1;

Fig. 4 is a plan view of that end of the machine shown in Fig. 2;

Fig. 5 is an elevational view of the preliminary feeding means which moves each bottle from an upright position to a horizontal position;

Figs. 6 and 7 show a part of the mechanism shown in Fig. 5 but in slightly different positions;

Fig. 8 is a plan view of the feeding means shown in Fig. 5;

Fig. 9 is a plan view of the means for moistening the paper as it is fed through the machine;

Fig. 10 is a plan view of part of the wrapping mechanism shown in Fig. 4;

Fig. 11 is a view similar to Fig. 10 but with the parts in a different position;

Fig. 12 is a section substantially on the line 42—42 of Fig. 3;

Fig. 13 is a section substantially on the line 13—13 of Fig. 3;

Fig. 14 is a section taken along the line 14—14 of Fig. 4;

Fig. 15 is a section taken substantially along the line 15—15 of Fig. 4;

Figs. 16, 17, 18 and 19 are views similar to Fig. 15 but with the parts arranged to show different positions of the wrapping means;

Fig. 20 is a view showing the operation of the means for folding the first flap over the bottom of the bottle;

Fig. 21 is a plan view showing the means for folding the second flap over the bottom of the bottle;

Fig. 22 is a plan view showing the means for folding the third flap over the bottom of the bottle;

Fig. 23 is an elevational view showing the means for raising the bottle into an upright position and for simultaneously making the last flap over the bottom of the bottle; and

Fig. 24 is a view showing the position of the flaps after the last flap has been folded over the bottom of the bottle.

Referring more particularly to Figs. 1 to 5, 55

inclusive, 1 represents the frame of the machine. This frame is adapted to support the various operating parts of the machine and has a cross section substantially as shown in Fig. 14. To this frame are bolted the various brackets which support the operating parts of the machine. A bracket 2 is secured by suitable means such as bolts 3 to one end of the frame 1, and rotatably mounted in this bracket is a shaft 4. A second shaft 5 is rotatably supported in brackets 6 on the upper part of the frame 1. Pulleys 7 and 8 are mounted on the shafts 4 and 5, respectively, and a conveyer belt 9 is trained over these pulleys, as best illustrated in Fig. 1. Two other shafts 10 and 11 are rotatably mounted in the bracket 2 and these shafts carry the pulleys 12 and 13, respectively, over which is trained the conveyer belt 14. The shaft 11 is driven by means of a chain 15 trained over a suitable sprocket 16 on the shaft 11 and over a suitable driving sprocket 17 on a shaft 18 driven directly from the drive shaft 19 by means of the bevel gears 20 and 21. This drive shaft 19 is driven by means of a motor 22 through the gears 23 and 24, clutch elements 25 and 26, and gears 27 and 28, the latter being mounted directly on the drive shaft 19.

Referring now more particularly to Figs. 5 to 8, inclusive, it will be noted that the drive shaft 11 has a sprocket 28 fastened thereto and at the rear end thereof, and this sprocket has a chain 29 trained thereover and over a sprocket 30 mounted on a shaft 31 in a suitable bracket 32 mounted on the bracket 2, as best illustrated in Figs. 5 and 8. The shaft 31 also carries a cam 33 which has a cam groove 34, as best illustrated in Fig. 5, the cam groove being located on the rear face of the cam. Pivoted to the bracket 32 at 35 is an arm 36 carrying a projection 37. A roller 40 38 is mounted on the projection 37 and engages the cam groove 34 so that when the cam is rotated, the arm 36 is oscillated about its pivot 35. Oscillation of the arm 36 causes the oscillation of an arm 39 mounted on the shaft 40 which latter is rotatably mounted in the bracket 32, the motion being transmitted from the arm 36 to the arm 39 by means of a connecting link 41. At the end of the shaft 40 opposite to that upon which the arm 39 is mounted, is pivoted a member 42 having a flange 43 on the front face thereof and a hollowed out portion 44 for the reception of a bottle, such as A.

A suitable support 45 for the bottles A extends along one end of the machine in a direction substantially parallel to the shaft 40. The bottles are fed along this support by any suitable means and are guided by suitable guiding elements 46 on opposite sides of the support 45. The means for feeding the bottles along the support 45 may be either manual means or mechanical means, but the feeding means must necessarily be such that it is capable of feeding one bottle to the recess 44 after each movement of the member 42 to the position illustrated in Fig. 5.

Assuming that the parts are in the position shown and that the clutch members 25 and 26 are in engagement, it will be readily seen that the shaft 31 will be given a continuous movement through the aforesaid driving connections with the drive shaft 19. This rotates the cam 33 and causes the oscillation of the member 42. The bottle A which is within the recess 44 of the member 42 when the member 42 begins its movement to the right, as viewed in Fig. 5, is moved to a position such as that shown in Fig. 6, the

projection 47 acting as a means for retaining the bottle within the recess 44 until the member 42 begins its return movement. The bottom of the bottle A rests on the endless belt 14, as the member 42 moves to the right and, as the member 42 begins its movement to its original position at the left, the bottle A is permitted to fall onto the endless belt 14, due to the fact that as the member 42 moves to the left, the projection 47 becomes disengaged from the bead or cap on the upper end of the bottle and the belt 14 aids in moving the lower end of the bottle to the right to assist the bottle in attaining its horizontal position on the belt. The second position of the bottle is represented as A¹ and in this position the bottle 15 is carried along with the belt 14 to the right.

When the bottle reaches the extreme right end of the upper horizontal section of the belt 14, it is deflected onto the belt 9 by means of a deflecting plate 48. The belt 9 moves in the same direction 20 as the belt 14 and carries the bottle into a position designated as A². In this position, the bottle is temporarily stopped by means of a stop member 49 mounted on a shaft 50 journaled in the bracket 6. The shaft 5 which drives the belt 9 is 25 driven by means of the chain 15, previously described, a suitable sprocket being mounted on the rear end of the shaft 5 adjacent the gear 50, the latter also being rigidly fastened to the shaft 5.

The shaft 50, upon which the stop member 49 is 30 mounted, has an arm 51 rigidly mounted thereon and this is connected by means of a suitable connecting link 52 to the arm 53 pivoted on the shaft 54. The arm 53 carries a suitable roller which engages a cam groove in the cam 55 in a manner similar to that in which the roller 38 engages the cam groove 34 in the cam 33. The cam groove is such as to give an up and down movement to the link 52 and thus cause the shaft 50 to be rocked. In Fig. 1, the link 52 is shown in its lowermost 40 position and in this position of the link 52, the stop member 49 has the end thereof engaging the bottom of the bottle located at the position A². When the link 52 moves upwardly, the bottle is permitted to be fed into the conveyer belt 56 from the conveyer belt 9, the gap therebetween being bridged by a roller 57 which has a peripheral speed greater than the linear speed of the belt 14, thus causing the bottle to be moved quickly off of the belt 14 onto the conveyer 56. The roller 57 is 50 mounted on the shaft 57' and driven by means of a gear 58' from the gear 139, which will later be described.

The conveyer belt 56 is trained over suitable pulleys 58 and 59 mounted on the shafts 60 and 61 journaled in suitable bearings in the brackets 62 and 63, respectively, and on the frame 1. The belt also runs over a suitable idle pulley 64 and motion is imparted thereto by means of the pulley 59 which is positively driven by means of a chain 65 trained over a sprocket 66 on the shaft 18 and a sprocket 67 (Fig. 4) on the shaft 61.

I will now proceed to describe the means for feeding the paper onto the conveyer 56, which feeding means is best illustrated in Figs. 1, 2 and 9. A bracket 68 is mounted on the right-hand end of the frame 1, as best illustrated in Fig. 2, and this bracket rotatably supports the shafts 69 and 70 upon which are mounted the rollers 71 and 72. The bracket 68 also carries an extension 73 which rotatably supports a shaft 74 upon which a roll of paper 75 is mounted. The paper 76 in the roll 75 is fed through a housing 77 under and around the roller 72 and then upwardly and around the roller 71. The paper 76 is then fed to 75

the cutting and feeding device designated generally as 78. This comprises brackets 79 and 80 fastened to the upstanding web of the frame 1 and these brackets are adapted to rotatably support the drums 81 and 82 respectively. The drums 81 and 82 carry the knives 83 and 84 which have cutting edges which co-operate to perform a shearing cut on the paper 76 as the knives rotate into the position illustrated in Fig. 1. Rollers 85 and 86 are adapted to feed the paper to the knives and these rollers are yieldingly held together by means of a coil spring 87, the upper roller 85 being permitted to move downwardly by suitable means and the roller 86 being rotatably supported by means of the shaft 88 mounted in the bracket 79. After the paper passes the cutting position, it passes over a guide plate 89 and this guide plate guides the paper in between the rollers 90 and 91, the rollers 90 being rotatably mounted on a shaft 92 journaled in the bracket 80, and the roller 91 being rotatably mounted on the outer end of an arm 93 normally urged upwardly by the spring 94 against the rollers 90.

25 The shaft 74 is free to rotate but may have suitable means to retard its rotation to prevent the paper being fed too rapidly. The shaft 70 is positively driven by means of a chain 95 trained over a sprocket on the shaft 70 and a sprocket 96 on the shaft 18. The shaft 69 has a gear 97 rigidly fastened thereto and meshing with a similar gear on the shaft 70 so that the shaft 69 will rotate in a reverse direction to the rotation of the shaft 70 in order to cause the proper feeding of the paper around the rollers 72 and 71. The shaft 88 carries a sprocket 98 and this sprocket is driven by means of a chain 99 trained thereover and over a sprocket 100 on the shaft 18. The chain 99 also passes over the idle pulley 101 and gears 92' and 82' mounted on the rear end of the shaft 92 and the rear end of the shaft which supports the drum 82, respectively. The shafts which support the drums 81 and 82 are interconnected by means of suitable gears, one of which is shown in Fig. 9 at 102, the other being located directly therebeneath on the shaft which supports the drum 82.

An arm 103 pivoted at 104 to the bracket 80 carries a plurality of rollers 105 which co-operate with the rollers 90 in feeding the paper through the paper feeding mechanism. After the paper passes between the rollers 90 and 105, it is guided over that section of the belt 56 supported on the drum 58, by means of the guide plates 106 and 107 and, from there, onto the top part of the conveyer 56 where it is in a position to receive a bottle such as the bottle indicated at A³ and to be wrapped therearound.

I prefer to moisten the paper prior to feeding the same through the machine and for this purpose, I provide the vaporizer 108 which is adapted to contain a suitable liquid, such as water, and a heating element 109 occupies a position within the vaporizer, and, in the preferred form of my invention, I use an electric heating element which is heated by a suitable electric current conveyed through the wires 110 from a source of electricity. The heating element vaporizes the water within the vaporizer 108 and the vapor escapes through the opening 111 in the top of the vaporizer. This opening is directly beneath the roll of paper 75 and the vapor comes into contact with the outer layer of paper on the roll and moistens the same a sufficient amount so that the same can stretch and so when the paper arrives at the

position where it is to be wrapped around the bottle, it is in a moist condition and is suitable for wrapping the bottle in a manner that will be described later.

Since it is very desirable to have the paper moistened only a certain amount, it is necessary that means be provided for preventing an excessive amount of vapor from coming into contact with the roll of paper 75 when the machine is stopped for any reason. In other words, if the machine was stopped and the vapor from the vaporizer permitted to escape and come into contact with the roll of paper 75, a considerable amount of moisture would be collected by the paper and would penetrate through the roll, perhaps, causing the paper to tear when the machine is again started. For this purpose, I provide a cover member 112 carried by means of the arm 113 on one arm 114 of a bell crank lever 115 pivotally mounted on a bracket 116. The other arm 117 of the bell crank is connected by means of a link 118 to an operating lever 119 rigidly mounted on a shaft 120 rotatably mounted in brackets 121 and 2 on the frame 1. The rear end of the shaft 120 carries an arm 122 upon which is a roller 123 which engages in the groove 124 in the collar 125 which is rigid with the clutch member 26. An operating handle 126 is rigidly attached to the shaft 120 and is used to rock the shaft 120 to cause the roller 123 to shift the clutch member 26 into and out of engagement with the clutch member 25. In Figs. 1 to 4, inclusive, the handle 126 is shown in the position which it occupies when the clutch members 25 and 26 are disengaged. In this position, the member 112 is located over the opening 111. When the handle 126 is moved to the right, as viewed in Fig. 1, the clutch members are thrown into engagement and the connecting link 118 rotates the bell crank 115 about its pivot and moves the cover member 112 into the position shown in Fig. 9 so that the vapor may escape from the vaporizer 108 and come into contact with the paper in the roll 75. This means is more effective than merely cutting off the current through the heating element since even if the current is cut off in the heating element at the time the machine is stopped, some of the liquid will be vaporized due to the residual heat in the heating element and the paper may become excessively moistened before the heating element stops vaporizing the liquid. Means can also be provided for automatically shutting off the current supplied to the wires 110 so that no great pressure will be developed within the vaporizer.

As the sheets of paper 76 are fed onto the conveyer belt 56 between the guides 106 and 107, the outer edges thereof are supported by the adjacent supporting members 127 and 128. Shortly after the paper leaves the space between the guide plates 106 and 107, it reaches the folding members 129 and 130 fastened by means of the screws 131 and 132, respectively, to the supporting members 127 and 128. The paper reaches the folding member 130 before it reaches the folding member 129, as will be clear from an inspection of Fig. 3. As the paper leaves the space between the guide plates 106 and 107, the bottle is fed from the position A² onto the upper surface of the paper due to the fact that at this instant the link 52 is moved upwardly by the cam 55 and this movement swings the stop member 49 to the right, thus releasing the bottle and the movement of the belt 9 and roller 57 moves the bottle over the roller 57 onto the upper surface of the paper.

A suitable gluing device is used to apply glue to one edge of the paper, that edge being the one which is folded over by the folding member 129. This gluing device comprises a suitable glue trough 133 mounted on the guide rod 134 and the rotating shaft 135 by means of the lugs 136 which surround the guide rod 134 and the rotating shaft 135. The rotating shaft 135 also carries a glue applying wheel 137 which passes through a slot 138 in the edge of the glue trough 133. An idle gear 139 meshes with the gear 50 on the shaft 5 and is rotated thereby. On the same shaft with the idle gear 139 is a sprocket over which is trained the chain 140, the chain also being trained over the sprocket 141 mounted on the shaft 135 so that the shaft 135 is rotated in a counter-clockwise direction as viewed in Fig. 1. The glue is carried through the slot 138 by the glue wheel and the sides of the slot tend to scrape the glue from the sides of the glue wheel 137 but permits a small amount of the glue to remain on the periphery of the wheel. This glue comes into contact with the upper edge of the sheet of paper located therebeneath and is deposited thereon as the paper passes underneath the wheel.

As the conveyer belt 56 moves the paper and bottle together to the right as viewed in Figs. 1 or 3, the folding member 130 turns the edge of the paper thereon so that the same is folded over the upper surface of the bottle. Shortly thereafter the edge of the paper above the folding member 129 is folded over in a similar manner and remains above the edge folded over the bottle by the folding member 130, in the manner best illustrated in Fig. 12. After leaving the folding members 129 and 130, the paper is held in the folded position against the bottle by means of the retaining members 142 and 143 and the lower retaining members 144 and 145. The lower retaining members 40 are urged upwardly to force the paper against the bottle by means of levers 146 and 147 pivoted to the blocks 148 and 149 rigid with the supporting members 128 and 127, springs 150 being used to rock the levers 146 and 147 about their pivots, as is best illustrated in Fig. 12 with reference to the lever 146. The upper retaining members 142 and 143 are each yieldingly urged against the paper folded over the upper part of the bottle by means of pivoted levers 151 yieldingly urged in a direction towards the bottles by means of the springs 152. The levers 151 are pivoted to the blocks 153 rigid with the supporting members 127 and 128. It is now necessary to pull the paper tightly about the bottle and glue the edges 55 154 and 155 together, the edge 155 being the one which has the glue applied thereto on the underside as viewed in Fig. 12.

Referring now more particularly to Figs. 4, 10, 11 and 14 to 19, inclusive, it will be noted that after the bottle with the paper wrapped therearound is carried past the retaining members 142 to 145, inclusive, it is brought into a position adjacent the wrapping members designated generally as 156 and 157. When the bottle first arrives at this position, the wrapping members 156 and 157 occupy the position shown in Fig. 14. The wrapping member 156 is carried by means of the arm 158 which has a roller 159 engaging a slot 160 in the member 161 which is slideable on the guide rod 162 rigidly secured to the bracket 163 mounted on the upper ledge 164 of the frame 1. A carriage 165 is slidably mounted on the square guide rod 166 and the circular guide rod 167 and is adapted to reciprocate along said guide rods. Pivoted at 170 to a ledge 168 of

the carriage 165 are a pair of bell cranks 169 adapted to be moved in unison by the connecting link 171 connected to one end of each of said bell cranks 169. One of the bell cranks has its other end pivotally connected at 172 to the arm 158. The free end of the other bell crank is pivotally connected at 173 to a member 174 fastened to the wrapping member 156. By this arrangement, the wrapping member 156 will always move through successive parallel positions. The carriage 165 also has a ledge 175 integral therewith to which are pivoted the bell cranks 176 and these are caused to move in unison by means of the connecting link 177 in the same manner as are the bell cranks 169. The bell cranks 176 also have one end pivotally connected to the plate 178. An arm 179 is also operatively connected to the plate 178 and has a roller 180 adapted to slide in the groove 181 in the member 182. The member 182 is rigidly connected to the shaft 183 slidable in a bearing 184 of the bracket 185 and a suitable bearing in the frame 1. The end of the shaft 183 opposite to that on which the member 182 is fastened, is provided with a member 186 rigidly secured thereto and having a guide groove in the lower end thereof which slides along the guide rod 187 rigidly fastened to the frame 1. This guide rod 187 prevents the shaft 183 from rotating but permits longitudinal movement thereof. The member 161 which slides on the guide rod 162 is also provided with a groove which slides along an auxiliary guide rod 188 so that the member 161 can move longitudinally on the shaft 162 without rotating about said shaft.

Referring more particularly to Fig. 14, it will be noted that the member 161 is connected by means of a link 189 to an arm 190 pivoted to the shaft 54. The arm 190 carries a roller 191 engaging a cam groove 192 in the cam 193. A link 194 is pivoted to the member 186 and to an arm 195 also pivoted on the shaft 54 and this arm 195 carries a roller 196 engaging a cam groove 197 in the cam 198. The cams 193 and 198 are arranged to move the wrapping members 156 and 157 in a predetermined timed relation so as to carry out the successive movements of these members, which will presently be described.

Before proceeding with a description as to the specific movements of the members 156 and 157 during the wrapping operation, attention is called to the fact that the members 156 and 157 can move longitudinally in a direction parallel to the movement of the belt 56 due to the fact that the carriage 165 is supported by the guide rods 166 and 167 and also because of the rollers 180 and 186 which operate in the grooves 181 and 160, respectively, to always maintain communication with the members 182 and 161, which impart motion to the wrapping members 157 and 156, respectively, in a direction transversely of the movement of the belt 56. The movement of the carriage 165 longitudinally of the belt 56 is accomplished by means of a link 199 pivotally connected to the carriage at 200 and to an arm 201 pivoted at 202 to the frame 1, this arm 201 carrying a roller 203 operating in the cam groove 204 of the cam 205. This cam 205 is rigidly connected to the shaft 18 and rotates therewith. The cam is so designed as to cause the wrapping members 156 and 157 to move along with the belt at substantially the same rate of speed during the time that these wrapping members are operating on the edges 154 and 155 of the 75

wrapping paper, the cam also serving to withdraw the wrapping members 156 and 157 after each successive bottle is wrapped so that the wrapping members will be ready to wrap the next bottle that comes along.

Bearing in mind the fact that the wrapping members move along with the belt at substantially the same rate of speed during the wrapping operation, I will now proceed to describe the successive movements of the wrapping members 156 and 157 in a direction transversely to the movement of the belt 56. Referring particularly to Figs. 15 to 19, inclusive, it will be noted, in Fig. 15, that the wrapping member 156 has a suitable projection or finger 206 rigidly fastened thereto and the wrapping member 157 has a finger 207 rigidly fastened thereto. These fingers 206 and 207 may be adjustable to position the forward edges thereof in the desired position so that they will most effectively engage the wrapping paper in the manner desired. The fingers 207 and 206 are in substantially the same position in Fig. 15 as they are in Fig. 14, the finger 207 having begun its movement to the right. In Fig. 16, the finger 207 has completed its movement to the right and in doing so has stretched the edge of the paper 154 tightly against the upper surface of the bottle and the finger 206 has begun its movement to the left, the edge 155 being thrown upwardly by the finger 207 into a position between the fingers 206 and 207. It will be noted by a careful inspection of Figs. 16 and 17 that the paper is cut long enough so that it extends slightly over the projection 208 on the bottle, and as the finger 206 presses the edge 155 against the bottle, the edge 154 is also pressed thereagainst by means of the finger 206 with a sufficient pressure to prevent the edge 154 from moving back to its original position and, to prevent the finger 207 from dragging the edge 154 back with it on its return movement to the left, I provide a cam roller 209 rotatably supported on a bracket 210 rigidly secured to the supporting member 128 and this roller is adapted to engage the cam member 211 which is so designed as to engage the cam roller 209 just as the finger 207 begins its return movement to the left and raises the finger 207 sufficiently so that it is clear of the edge 154 of the paper, as best illustrated in Fig. 17. In order to permit the finger 207 to move upwardly, I mount a plate 178' loosely on the plate 178 by means of the screws 212 which permit a free vertical movement of the plate 178. Pins 213 also are mounted on the plate 178 and these pins have springs 214 surrounding them for the purpose of yieldingly urging the plate 178 downwardly against the plate 178. These springs, however, permit upward movement of the plate 178' due to the cam action between the cam 211 and roller 209.

The continued movement of the finger 206 to the left wraps the edge 155 over the edge 154 and the glue on the under surface of the edge 155 secures the edges 154 and 155 together in the manner illustrated in Figs. 18 and 19. In Fig. 19, it will be noted that the finger 207 is fully retracted and that the finger 206 has completed its movement to the left. The finger 206 is preferably made of some slightly yielding material and the finger 207 may also be made of slightly yielding material although, because of the fact that the plate 178 can yield upwardly, it is not absolutely necessary that the finger 207 be flexible at all.

Having thus described how the edges 154 and 155 are wrapped around the bottle, I will now

proceed to explain how the machine folds the paper about the bottom of the bottle.

Referring more particularly to Figs. 2, 4 and 20, it will be noted that when a bottle reaches the position A⁴, the various folding members operate successively to fold the paper over the bottom of the bottle. The paper which protrudes over the end of the bottle is first folded downwardly from the top edge of the bottle against the bottom thereof by means of the folding element 215 mounted on one arm of the bell crank lever 216 pivoted at 217 to the bracket 218 which is in turn secured to the bracket 219 on the frame 1. The other arm of the bell crank lever 216 is connected by means of a link 220 to an arm 221 secured to one end of a shaft 222 rotatably mounted in a bracket 223, the other end of the shaft 222 carrying an arm 224 connected by means of a link 225 to an arm 226 pivoted on the shaft 54 and carrying a guide roller 227 adapted to ride in a suitable cam groove in the cam 228. The cam 228 imparts a rocking motion to the bell crank 216 through the connections just described and, as the member 215, secured to the bell crank 216, moves downwardly, it engages the paper protruding over the end of the bottle and folds it downwardly against the bottom thereof to produce a fold such as that illustrated in Fig. 20.

As the folding member 215 begins its upward movement, a second folding element 229 begins its movement toward the paper protruding over the bottom of the bottle. This folding element 229 is mounted on a pair of plungers 230 and 230', the plunger 230 being yieldingly urged to the right by means of a spring 231 abutting against the collar 232. The plunger 230 is guided in a suitable bearing in the lug 233 and the plunger 230' is guided in a suitable bearing in the lug 233 and in the bearing 234. The lug 233 and the bearing 234 are integral with the bracket 235. This bracket 235 is carried by means of a member 236 rigidly secured to a shaft 237 and guided by means of a guide rod 238 rotatably mounted in the bearing 239 in the bracket 219. The shaft 237 extends to the rear end of the bracket 219 and is slidably mounted therein. A link 240 is pivotally connected to means on the shaft 237 and to the projection 241 on the arm 242 pivoted to the shaft 54, and the arm 242 also carries a roller 243 which engages a suitable cam groove in the cam 244 and the movement of the arm 242 is transmitted through the link 240 to the shaft 237. As before stated, the shaft is given a reciprocating movement in timed relation to the movement of the other elements. This timed movement of the shaft 237 brings the face 245 of the bracket 235 into engagement with the side of the partially wrapped bottle and simultaneously brings the folding element 229 into the position shown in Fig. 21. It will be noted that the folding element 229 is recessed at 246 so that the folding element 229 can be in position before the folding element 215 is completely withdrawn, or the folding elements 215 and 229 may be brought into engagement with the wrapping paper simultaneously. However, it is preferred that they be brought into engagement successively, even though there is only a small interval of time between the movement of each element into operative position.

The movement of the bracket 235 is not stopped when it comes into engagement with the bottle in the manner illustrated in Fig. 21, but is continued until the bottle is moved from the belt 56 to the belt 247 travelling in a direction par-

allel thereto. The belt 247 is supported by means of a pulley 248 on the shaft 61 which carries the pulley 59 and is suitably supported by a similar pulley, not shown, at its other end. Motion 5 is imparted to the belt 247 through the shaft 61 driven by the chain 65 from the shaft 18.

As the partially wrapped bottle is moved over onto the belt 247, the paper is given its third fold over the bottom of the bottle by means of 10 the folding member 249 carried by the arm 250 pivoted at 251 to the frame 1. As the bottle is moved onto the belt 247, the folding member 249 is in the position shown in Fig. 22 and the movement of the bottle relative to the folding member 15 249 makes the third fold of the paper against the bottom of the bottle. The bracket 235 immediately thereafter returns to its original position and carries with it the folding member 229.

A link 252 is pivotally connected at 253 to the 20 arm 250 and to an arm 254 adapted to be rocked about the shaft 54 by means of a roller on the arm 254 engaging a suitable cam groove in the cam 255. The rocking movement of the arm 254 about the shaft 54 is imparted to the arm 250 25 through the means of the link 252. The arm 250 remains in the position shown in Figs. 4 and 22 until the bottle is stood on end as the folding member 249 is adapted to assist in raising the bottle to an upright position.

30 The bottle is raised to an upright position by means of an arm 256 pivoted on the shaft 238 and this arm 256 carries a pin 257 at the free end thereof. A link 258 is operatively connected to arm 256 and an arm 259 pivoted to the shaft 35 54 and rocked about said shaft by a suitable roller mounted on the arm 259 adapted to engage in a suitable cam groove in the cam 260. The link 258 is pivotally connected to the arm 256 and vertical movement of the link 258 rocks the 40 arm 256 about the shaft 238 and as this arm 256 rotates in a clockwise direction, the pin 257 engages the underside of the bottle and tends to raise it into an upright position, the folding member 249 acting as a stop to prevent the belt 45 247 from carrying the lower edge of the bottle to the right, as viewed in Fig. 23. It will be noted that as the bottle is raised to the upright position shown in Fig. 23, the remaining unfolded portion of the wrapping paper protruding past the 50 bottom of the bottle is folded against the bottom of said bottle to complete the folding operation. As soon as the bottle has been raised into an upright position, the cam 255 moves the arm 259 so as to withdraw the folding member 249 from 55 in front of the bottle and the bottle, being no longer restrained, is permitted to be carried along the belt 247 to a position where the wrapping of the top unfolded edges of the wrapping paper is accomplished either by hand or by suitable 60 mechanical means. Since the folding of the upper parts of the wrapping paper forms no part of the present invention, the same has not been illustrated. Fig. 24 illustrates how the wrapping paper is folded against the bottom of the bottle.

65 I will now proceed with a brief description of the operation of the machine. The motor 22 is started and this drives the gear 24 and clutch member 25. By shifting the lever 126 to the left (Fig. 1) the clutch member 26 is thrown into engagement with the clutch member 25 thereby driving the shaft 19 through the gears 70 27 and 27 as previously described. Motion is transmitted to the shaft 18 from the shaft 19 by means of the bevel gears 20 and 21. Since 75 the cams 193, 198, 228, 255, 260 and 244 are

rigidly mounted on the shaft 19, they will rotate therewith to perform their various functions. Rotation of the shaft 18 drives the sprockets 66, 100 and 96 rigidly fastened thereto and these sprockets, in turn, drive the chains 65, 99 and 95, respectively, thus causing the belts 14, 9, 56 and 247 to rotate in the manner referred to, the upper run of each of these belts travelling to the right, as viewed in Figs. 1 and 2.

Paper is fed from the roll 75 through the feeding means to the upper surface of the belt 56 and bottles are fed from the support 45 to the oscillating member 42 and, from there, onto the belt 14, the oscillating member 42 moving the bottles from a vertical to a horizontal position 15 so that the bottles will travel along the belts 14, 9 and 56 in a horizontal position. The stop member 49 temporarily restrains the bottles at the position A² and when the stop member is moved out of the way by the cam 55, the bottles 20 will move onto the paper which, by this time, has been fed into a position just to the right of the pulley 58, by means of the feeding mechanism previously described in detail. The paper 25 is in a moist condition and, as it passes the glue applying wheel 137, glue is applied to one edge thereof.

The bottle with the wrapping paper then passes through the folding members 130 and 129 and the retaining members 142, 143, 144 and 145 30 to preliminarily position the edge 154 below the edge 155. As the bottle begins its movement, the wrapping members 157 and 156 successively engage the edges 154 and 155, respectively, to draw the wrapping paper tightly about the bottle 35 and to force the glued surface on the under side of the edge 155 into engagement with the upper surface of the edge 154, the wrapping operation taking place while the bottle is moving along the conveyer 56. The folding members 215, 229 40 and 249 thereafter successively engage the unfolded portion of the paper extending outwardly from the bottom of the bottle and fold the same against the bottle, leaving one remaining part thereof to be folded when the bottle is raised 45 into an upright position. As the bottle is raised into an upright position by the pin 257 on the arm 256, the last fold is made in the manner previously described, and as soon as the cam 255 withdraws the folding member 249, the bottle 50 will be carried along the conveyer belt 247 to a position where the wrapping paper may be securely wrapped around the neck of the bottle either by hand or by mechanical means. As the paper dries, the same tends to contract and will 55 draw the paper tightly about the surface of the bottle.

It will be obvious that various modifications can be made in my device without departing from the spirit and scope of the invention, and 60 my device is capable of being used for wrapping articles other than bottles and therefore I do not wish to limit the scope of the claims to merely a bottle wrapping machine. Furthermore, the paper may be fed to the machine by 65 hand and may be moistened in other ways than that disclosed, the essential feature of novelty being that the paper is moistened before being wrapped about the article so that when the paper is dried, the same will be drawn tightly about 70 the bottle.

Other means may be used to wrap the paper about the bottle while in motion, and the means shown is merely a preferred form of wrapping means for this purpose. If desired, bottles may 75

be fed to the machine while in a horizontal position, and, if desired, I may provide a fourth folding member somewhat similar to the folding members 215, 229 and 249 to fold the last portion of the wrapping material against the bottom of the bottle instead of doing this simultaneously with the raising of the bottle to an upright position.

While I have shown cam means for operating the various elements of my machine, I do not wish to be limited to this type of control as it is obvious that other well known types of means for controlling the operation of the various parts may be used if desired.

Obviously those skilled in the art may make various changes in the details and arrangement of parts without departing from the spirit and scope of the invention, as defined by the claims hereto appended, and I wish therefore not to be restricted to the precise construction herein disclosed.

Having thus fully disclosed an embodiment of my invention, what I claim and desire to secure by Letters Patent of the United States is:—

1. An article wrapping machine for wrapping articles having an outer rigid surface comprising a vaporizer, a support for wrapping material, a feeding mechanism for said wrapping material, means for directing the vapor from said vaporizer to said wrapping material, and means for stretching said material snugly around an article while said material is moist.

2. An article wrapping machine comprising a vaporizer, a heating element in said vaporizer, feeding means for a wrapping material, and means for directing vapor from said vaporizer to said wrapping material as it is being fed through the machine.

3. An article wrapping machine comprising a vaporizer, a heating element in said vaporizer, feeding means for a wrapping material, means for directing the vapor from said vaporizer to said material while the machine is in operation, and means for rendering said directing means inoperative when said machine is stopped.

4. A bottle wrapping machine comprising a vaporizer, means for feeding wrapping material to said machine so that bottles may be wrapped thereby, and means for permitting the vapors from said vaporizer to come into contact with said material when said machine is in operation, said means also rendering said vaporizer inoperative for the purposes set forth when the machine is stopped.

5. An article wrapping machine comprising an endless conveyer, means for feeding a sheet of wrapping material onto said conveyer, means for moistening said wrapping material, means for feeding an article onto said wrapping material, means for applying glue to said wrapping material near one edge thereof, and means for stretching the opposite ends of the material about the article while the article is moving with said endless conveyer to bring the glue between the opposite edges thereof, whereby the material cannot become loosened when it dries but will cause the stretching of the material over the surface of said article when the material dries.

6. A bottle wrapping machine comprising a conveyer, means for partially wrapping a bottle in wrapping material while said bottle lies on a side thereof while on said conveyer, means for moving said article off of said conveyer onto a second conveyer and simultaneously folding an

additional portion of said wrapping material about said bottle, means for raising said bottle into an upright position while on said second conveyer, and means for preventing movement of said bottle along said second conveyer until said bottle is in an upright position, the movement of the bottle to an upright position on said conveyer causing another portion of said wrapping material to be folded against the bottom side of said bottle.

7. A bottle wrapping machine comprising means for partially wrapping a piece of wrapping material about a bottle so that the sides thereof are covered by said wrapping material and so that a portion of said wrapping material extends outwardly from an end surface of said bottle, means for folding said extending portion of said wrapping material against said end of said bottle, and additional means for folding another portion of said extending portion against said end of said bottle, said first means for folding said extending portion having a recess therein to permit the second means for folding said extending portion to occupy a position in overlapping relation with said first means for folding said extending portion.

8. A wrapping machine comprising means for wrapping a sheet of paper partially about an article with a portion of said paper extending outwardly from end surface of said article, a folding means for folding one portion of said extending portion against the bottom of the article, a second folding means for folding a second portion of said extending portion against the bottom of the article, a third folding means for folding a third portion of said extending portion against the bottom of the article, said first folding means being adapted to move said partially wrapped article into a position adjacent said third folding means so that said third folding means may be operable to fold said extending portion in the manner described, and means for changing the angular position of the article to thereby fold the remaining portion of said extending portion against the bottom of the article.

9. A wrapping machine comprising means for moving a piece of wrapping material along a predetermined path, means for feeding an article to be wrapped onto said wrapping material, means for folding opposite edges of said material over said article in overlapping relation to each other, means moving at substantially the same speed and in the same direction as said wrapping material and article for moving one of said edges in a direction about said article to pull said wrapping material tightly about said article, said last-mentioned means being given an additional movement transversely to the movement of said wrapping material for moving said last-mentioned edge portion in the manner specified.

10. A wrapping machine comprising means for moving a sheet of wrapping paper along a definite path, means for feeding an article onto said paper, means for wrapping said article while the paper and article are in motion along said path comprising a pair of members successively operable to fold opposite edge portions of said paper over said article in overlapping relation to each other, means for moving one of said edge portions in such a direction about said article as to cause said paper to be pulled tightly against said article, and an additional means for moving the other edge about said article so as to pull said last-mentioned edge in a direction to cause the paper

to be pulled tightly about said article and to press said last-mentioned edge against said first-mentioned edge.

5 11. A device as claimed in claim 10 in which the means for moving the first-mentioned edge about the article is raised out of contact with that edge while the means for moving said second-mentioned edge about said article is operating in the manner set forth.

10 12. An article wrapping machine comprising a moving support, folding members adapted to move in the same direction and at substantially the same speed as said support, means for partially wrapping a piece of paper about an article 15 while said article is on said support, and means for drawing said paper tightly about said article comprising a pair of wrapping members one of which is adapted to fold one of two overlapping edges of said paper in a direction so as to cause 20 said paper to be pulled tightly about said article, and the other of said wrapping members being thereafter operative to move the other of said overlapping edges of said paper about said article in a direction to pull said paper tightly 25 about said article and to press the overlapping edges into engagement with each other, said first-mentioned wrapping member being movable out of engagement with said first-mentioned edge as said second-mentioned wrapping member is 30 moved to engage said second-mentioned edge and move said second-mentioned edge in the manner described.

13. A wrapping machine comprising a plurality of endless conveyors arranged in tandem relation 35 and moving in substantially the same direction, means for feeding a sheet of wrapping material upwardly between said conveyors and onto one of said conveyors, means for feeding articles supported on a side thereof to said machine adjacent the other of said conveyors, means to thereafter move said articles to support said articles on said last-mentioned conveyor and simultaneously move said articles so that they are supported on another side thereof, means for moving said last-mentioned conveyor at a speed greater than said first-mentioned conveyor, means for temporarily stopping the movement of said articles along said conveyor upon which they are first supported, means to thereafter release 45 said articles to permit said faster moving conveyor to move said articles onto the slower moving conveyor and onto the wrapping material on said last-mentioned conveyor, and means for wrapping said material about said articles.

55 14. A wrapping machine comprising a plurality of endless conveyors arranged in tandem relation and moving in substantially the same direction, means for feeding a sheet of wrapping material upwardly between said conveyors and onto one of said conveyors, means for feeding articles supported on a side thereof to said machine adjacent the other of said conveyors, means to thereafter move said articles to support said articles on said last-mentioned conveyor and simultaneously move said articles so that they are supported on another side thereof, means for moving said last-mentioned conveyor at a speed greater than said first-mentioned conveyor, means for temporarily stopping the movement of 60 said articles along said conveyor upon which they are first supported, means to thereafter release said articles to permit said faster moving conveyor to move said articles onto the slower moving conveyor and onto the wrapping material on said last-mentioned conveyor, and means for 65

wrapping said material about said articles while said articles are in motion.

15. A device as claimed in claim 13 in which means are provided for moistening the wrapping material prior to moving said material onto said 5 first-mentioned conveyor.

16. A wrapping machine comprising a conveyor, means for feeding wrapping paper onto said conveyor, means for feeding articles to be wrapped onto said wrapping paper, means for applying glue to one edge of said wrapping paper, means for moistening said wrapping paper prior to placing the same on said conveyor, means for folding opposite edges of said wrapping paper about said article with the glued edge in overlapping relation to the opposite edge of said wrapping paper, means for folding a remaining unfolded portion of said wrapping paper against said article, and means for changing the angular position of said article and for simultaneously 20 folding a still unfolded portion of said wrapping paper against said article.

17. A device as called for in claim 16 in which a clutch is provided for starting and stopping the movement of said machine, and in which a means 25 is provided for rendering said paper moistening means inoperative when the clutch is disengaged and to automatically render said paper moistening means operative when the clutch is engaged, comprising operative connections between said 30 clutch and said moistening means.

18. A bottle wrapping machine comprising a support for supporting the wrapping material, means for placing a bottle to be wrapped on said material, means for wrapping a portion of the 35 material about a portion of said bottle with a portion of the wrapper extending outwardly from a side of said bottle contiguous to that upon which the bottle is wrapped, means for tilting said bottle about the edge formed by said last mentioned side and the side upon which said bottle is resting whereby the extending portion of said material is folded against said aforementioned side which is contiguous with the side of said bottle upon which the bottle was originally supported.

19. In a bottle wrapping machine, the combination with a continuously moving conveyor adapted to support a sheet of wrapping material, means for feeding articles to be wrapped 50 onto said material while said conveyor is in motion, means for partially folding the material about said article as it moves with said conveyor, and supplemental means for folding another portion of said wrapping material about 55 said article over the end thereof which faces in the direction of bodily movement of said article comprising an abutment arranged in the path of movement of said article, a second conveyor, and means adjacent said second conveyor for 60 folding another portion of said material against said last mentioned side when said article is moved onto said second conveyor, and means movable transversely to the path of movement of said article while on said first conveyor for 65 feeding said articles onto said second conveyor, said last mentioned means having a limiting stop associated therewith for limiting the movement of said article on said first conveyor so that said article will occupy a predetermined position 70 on said second conveyor when said article is moved onto said second conveyor.

20. A device as claimed in claim 19 in which said article is moved angularly so that the same is supported by said last mentioned side thereof 75

instead of that side upon which said article was originally supported, said article of its own weight thereby wrapping another portion of the material against said side.

5 21. An article wrapping machine comprising a support for the wrapping material, means for feeding wrapping material onto said support, means for feeding articles onto said wrapping material, means for wrapping material about 10 said articles while on said support with portions thereof extending from the sides of said article, means for folding some of the free ends of said wrapping material against the adjacent side of said article but leaving a portion of said wrapping material extending away from said side, a second support and an adjacent turning mechanism, means for feeding said articles onto said turning mechanism and conveyer while said article is wrapped in the manner last set forth, 15 means for actuating said second support, means for temporarily restraining the movement of said articles with said second support until after said article has been turned by said turning means, means for turning said article by said turning 20 means so that said article is supported by said last mentioned side, and by the weight thereof accomplishes the folding of the last portion of said material extending outwardly from that side, said extending portion being folded against said 25 last mentioned side, and means for thereafter releasing said restraining means so that said article is conveyed away by said second support.

22. In a wrapping machine, the combination with means for feeding an article through said machine, of means for feeding a sheet of wrapping material onto said feeding means, means for feeding articles onto said wrapping material, and means to thereafter move opposite edges of said wrapping material about said article in 30 overlapping relation with each other while said article is in motion, means for applying glue to one of said overlapping edges of said wrapping material, and means for pressing said overlapping edges firmly together when the same are 35 in overlapping relation to seal said wrapper about said article, said last mentioned means acting also to simultaneously stretch the material tightly about the articles.

23. In an article wrapping machine, the combination with a pair of conveyers arranged in 35 series with each other, a continuously moving member between said conveyers, one of said conveyers being adapted to receive the articles and convey the same toward the other of said conveyers over said continuously moving member, restraining means arranged between said continuously moving member and said second conveyer for restraining articles from moving onto said second conveyer until a predetermined time, 40 means for rendering said restraining means inoperative so as to permit said continuously moving member to move said articles onto said second conveyer, means for feeding a sheet of material onto said second conveyer in position 45 to receive the article fed thereon by said continuously moving member, whereby said articles are fed onto said second conveyer in spaced relation with each other, and means for maintaining a continuous supply of articles for said continuously moving member.

24. A device as claimed in claim 23 in which said second mentioned conveyer is moving at a faster rate of speed than said first conveyer.

25. In a wrapping machine, the combination 75 with a pair of endless conveyers arranged in

tandem spaced relation with each other, a continuously rotating roller between said endless conveyers with the upper surface thereof substantially in line with the upper surfaces of said endless conveyer, a restraining means between said roller and one of said conveyers, means for feeding bottles onto the other of said conveyers, means for feeding wrapping material onto the first of said conveyers, said second conveyer conveying bottles onto said rollers against said restraining means, and means for releasing said restraining means to permit said rollers to feed said bottles onto wrapping material on said first mentioned conveyer.

26. The method of wrapping which comprises the steps of feeding the wrapping material continuously along a predetermined path to a wrapping position, and applying moisture to the wrapping material only while the same is in motion and at a point sufficiently removed from said wrapping position to enable the moisture supplied to said wrapping material to expand the same in the plane thereof before the wrapping material reaches said wrapping position.

27. The method of wrapping which includes the steps of feeding the wrapping material in a continuous web along a predetermined path to a wrapping position and applying moisture in the form of water vapor to the wrapping material at a given point in its path of travel in sufficient quantities and sufficiently removed from the wrapping position to enable the moisture to penetrate the wrapping material and cause the same to expand appreciably before it reaches said wrapping position and only while the web is in motion, and automatically stopping the application of water vapor to said web when said web comes to rest.

28. An article wrapping machine comprising a vaporizer, a heating element for said vaporizer for vaporizing a liquid adapted to be contained in said vaporizer, feeding means for feeding wrapping material to a wrapping position, and means for directing vapor from said vaporizer to said wrapping material as it is being fed through the machine in sufficient amounts to cause penetration of the material by said vapor before the material reaches said wrapping position, whereby said material expands appreciably before the same is used to wrap articles.

29. A bottle wrapping machine comprising a conveyer, means for partially wrapping a bottle in wrapping material while said bottle lies on a side thereof, while on said conveyer, means for moving said article off said conveyer onto a second conveyer, and simultaneously folding an additional portion of said wrapping material about said bottle, means for raising said bottle into an upright position while on said second conveyer, and means for preventing movement of said bottle along said second conveyer until said bottle is in an upright position, the movement of the bottle to an upright position on said conveyer causing another portion of said wrapping material previously projecting from the end thereof on which the bottle rests when in upright position to be folded against said bottle.

30. A wrapping machine comprising means for moving a sheet of wrapping paper along a definite path, means for feeding an article onto said paper, means for wrapping said article while the paper and article are in motion along said path comprising a pair of members successively operable to fold opposite edge portions of said paper over said article in overlapping relation to each other, means for moving one of said edge por-

tions in such a direction about said article as to cause said paper to be pulled tightly against said article, and an additional means for moving the other edge about said article so as to pull said last-mentioned edge in a direction to cause the paper to be pulled tightly about said article and to press said last-mentioned edge against said first-mentioned edge, said means for moving the edge portions into overlapping relation with each other being movable with the article along its path of movement at substantially the same speed as the article while said means are moving the edge portions into overlapping relation with each other.

31. A wrapping machine comprising means for moving a sheet of wrapping paper to a wrapping position, means for feeding an article onto said paper, and means for wrapping said article with said paper comprising a pair of members successively operable to fold opposite edge portions of said paper over said article in overlapping relation to each other, means for moving one of said edge portions in such a direction about said article as to cause said paper to be pulled tightly against said article, and an additional means for moving the other edge about said article so as to pull said last-mentioned edge in a direction to cause the paper to be pulled tightly about said article and to press said last-mentioned edge against said first-mentioned edge.

32. In a wrapping machine, the combination with a conveyer for conveying an article along a predetermined path, means for feeding a sheet of wrapping material onto said conveyer, means for feeding an article onto said wrapping material with the opposite edges thereof extending outwardly from said article in a direction substantially at right angles to the path of movement of said conveyer, folding members arranged on opposite sides of said conveyer for folding said extending edges upwardly over the sides of the article, and additional folding members for moving the upwardly extending edges of the wrapping material over the upper side of said article into overlapping relation with each other, said additional folding members each being mounted for movement in a direction parallel to the direction of movement of said conveyer and also for movement at right angles to the path of movement of said conveyer, means for actuating said folding members in the direction of said conveyer at substantially the same speed as said conveyer, while the said additional folding members are being moved into operative positions against the edges of the wrapping material and during the folding of the opposite edges about said article, and means for moving said additional folding members into and out of operative positions.

33. A device as claimed in claim 32 in which the means for moving the folding members in the direction of the conveyer movement comprises a slide movable during the folding operation of said additional folding members at a speed substantially equal to the speed of movement of said conveyer upon which slide the said folding members are both mounted with permissible movement with respect to said slide in a direction substantially parallel to the plane of movement of said conveyer and at substantially right angles to the direction of movement of said conveyer, whereby said additional folding members can be moved by the actuating means therefor in a direction toward operative position while said slide is moving substantially in unison with said conveyer.

34. In a wrapping machine, the combination with an endless conveyer, means for moving said

endless conveyer along a predetermined path, means for feeding a wrapper onto said conveyer, means for feeding an article onto said wrapper, means for moving the edges of the wrapper extending outwardly in the direction of the sides of the conveyer, upwardly over the sides of said article, and additional folding means for moving said edges into overlapping relation with respect to each other while said conveyer is moving, comprising a slide movable substantially parallel to the path of movement of said conveyer during the operative movement of said additional folding members, a pair of bell cranks carried by said slide arranged on one side of said conveyer, a pair of bell cranks arranged on the other side of said conveyer, said pairs of bell cranks being pivoted for movement in planes substantially parallel with the plane of movement of said conveyer and the bell cranks of each pair being constrained to move in parallel relation with respect to each other by a connecting link, corresponding ends of each pair of bell cranks carrying the additional folding member on the respective side of said conveyer, whereby rocking of said bell cranks about their pivots causes movement of the said additional folding members to and from operative positions, and means for moving said bell cranks about their pivots during the movement of said slide.

35. In a wrapping machine, the combination with an endless conveyer, means for moving said endless conveyer along a predetermined path, means for feeding a wrapper onto said conveyer, means for feeding an article onto said wrapper, means for moving the edges of the wrapper extending outwardly in the direction of the sides of the conveyer, upwardly over the sides of said article, and additional folding means for moving said edges into overlapping relation with respect to each other while said conveyer is moving, comprising a slide movable substantially parallel to the path of movement of said conveyer during the operative movement of said additional folding members, a pair of bell cranks carried by said slide arranged on one side of said conveyer, a pair of bell cranks arranged on the other side of said conveyer, said pairs of bell cranks being pivoted for movement in planes substantially parallel with the plane of movement of said conveyer and the bell cranks of each pair being constrained to move in parallel relation with respect to each other by a connecting link, corresponding ends of each pair of bell cranks carrying the additional folding member on the respective side of said conveyer, whereby rocking of said bell cranks about their pivots causes movement of the said additional folding members to and from operative positions, and means for moving said bell cranks about their pivots during the movement of said slide comprising members having slots therein substantially parallel to the path of movement of said conveyer and mounted for movement to and from said conveyer but in the direction of movement of said conveyer, means for reciprocating said members in timed relation to the movement of said conveyer, and members rigidly connected to respective ones of said additional folding members having projections thereon extending into the slots in said members, whereby the movement of said members to and from said conveyer actuates said additional folding members and their respective bell cranks.

36. In a wrapping machine, the combination with means for feeding a continuous web of wrapping material along a predetermined path, a hood

arranged over said web at one point in the path of travel thereof, and a vaporizer arranged beneath said hood for directing vapors into contact with the web passing under said hood.

5 37. In a wrapping machine, the combination with means for supporting a roll of wrapping material, and a vaporizer adapted to direct a vapor against a roll of wrapping material arranged on said supporting means to moisten the outer 10 layer of wrapping material as the wrapping material is unwound from said roll.

15 38. In a wrapping machine, the combination with means for supporting a roll of wrapping material, a vaporizer adapted to direct a vapor against a roll of wrapping material arranged on 20 said supporting means to moisten the outer layer of wrapping material as the wrapping material is unwound from said roll, and means for preventing the vapors from reaching said roll of wrapping material while the roll is at rest.

25 39. In a wrapping machine, the combination with means for supporting a roll of wrapping material, a vaporizer adapted to direct a vapor against a roll of wrapping material arranged on 30 said supporting means to moisten the outer layer of wrapping material as the wrapping material is unwound from said roll, and means for automatically preventing said vapors from reaching said roll of wrapping material if and when the movement of the wrapping material along its path of movement ceases.

35 40. An article wrapping machine for wrapping articles comprising a conveyer, means for feeding wrapping material previously expanded by applying moisture thereto on to said conveyer, means for feeding an article on to said wrapping material after it is expanded, and means for drawing said expanded wrapping material snugly about said article while the article is carried by 40 said conveyer.

45 41. An article wrapping machine for wrapping articles having a substantially incompressible outer portion, and comprising an endless conveyer, means for feeding a sheet of wrapping material to a wrapping position, means for moistening the wrapping material sufficiently to expand the same before the wrapping material reaches said wrapping position, means for feeding an article on to said wrapping material 50 while in expanded moist condition, and means for drawing said material tightly about said article while said conveyer is moving said article along on a predetermined path.

55 42. The method of wrapping articles comprising the step of feeding an article on to a flat sheet of wrapping material, saturating said wrapping material sufficiently before the wrapping operation to cause the same to expand appreciably in the direction of the plane thereof, thereafter snugly wrapping the wrapping material around said article while the same is in moist expanded condition, and thereafter drying said

material, whereby the same will stretch itself tightly over the surface of said article.

43. The method of wrapping articles comprising the steps of saturating a sheet of wrapping material with moisture sufficiently before the 5 wrapping operation to cause the same to expand appreciably in the direction of the plane thereof, snugly drawing said wrapping material about said article with opposite edges of the material arranged in overlapping relation with each other 10 while the material is still moist, sealing the overlapping edges of the material together while the wrapping material is still moist, and thereafter drying said wrapping material.

15 44. The method of wrapping articles comprising the steps of moving a sheet of wrapping material to a wrapping position and moistening the sheet sufficiently before it reaches the wrapping position to cause the same to expand appreciably in the direction of the 20 plane thereof, folding said wrapping material about said article so that opposite edges thereof are arranged in overlapping relation with each other while the material is still moist, sealing the overlapping edges of said wrap- 25 ping material together, folding other portions of said wrapping material snugly against said article while the material is still moist, and thereafter drying said material to stretch the same tightly over the outer surface of said article. 30

35 45. The method of wrapping articles comprising the steps of feeding a continuous web of material along a given path toward a wrapping position, moistening said wrapping material with sufficient moisture at a point far enough removed from the wrapping position to cause the moisture to penetrate and expand the material appreciably before the material reaches the wrapping position, the moistening of said wrapping material taking place during the feeding of the 40 same in the continuous web formation as the material passes a given point, and while the same is in motion, stopping the further moistening of the material if and when said material comes to rest, cutting said material while still 45 moist, and before the same reaches said wrapping material, into sheets, wrapping said sheets snugly about said articles while said sheets are still moist and expanded, and thereafter drying the wrapping material. 50

46. An article wrapping machine comprising a conveyer for conveying an article to be wrapped, means for partially wrapping a piece of wrapping paper about the article while the article is on the conveyer, means for moving the article 55 off said conveyer onto a support, means for shifting said article while on said support to support the article on a different side thereof and to simultaneously fold a remaining free portion of said wrapping paper against said different 60 side.

MICHAEL J. MILMOE.
